PORABLE TAPE PLAYER

Richard H. Seager, Manlius, N.Y., assignor to
General Electric Company

Filed June 23, 1971, Ser. No. 156,173

Term of patent 14 years

Int. Cl. D14—01

U.S. Cl. D26—14

FIG.1

FIG.2

FIG.3

FIG.4

FIG.5

FIG.6

FIG.7

FIG. 1 is a front, top and side perspective view of a portable tape player showing left and right units in the hinged open position, showing my new design;

FIG. 2 is a top plan view in the closed position;

FIG. 3 is a bottom plan view in the closed position;

FIG. 4 is a rear elevation view of the left unit;

FIG. 5 is a right side elevation view in the closed position;

FIG. 6 is a rear elevation view of the right unit; and

FIG. 7 is a left side elevation view in the closed position.

I claim:

The ornamental design for a portable tape player, as shown.
